UNITED STATES PATENT OFFICE.

JAMES W. HINE, OF JAMESTOWN, NEW YORK.

LIBRARY-SHELVING.

1,059,464.

Specification of Letters Patent. Patented Apr. 22, 1913.

Application filed May 29, 1909. Serial No. 499,219.

To all whom it may concern:

Be it known that I, JAMES W. HINE, a citizen of the United States, and resident of Jamestown, in the county of Chautauqua, 5 and State of New York, have invented certain Improvements in Library-Shelving, of which the following is a specification.

This invention relates to library shelving.

The objects of this invention are to con-

10 struct the shelving so that all binding of the shelves on the uprights is prevented; to overcome the necessity of entirely withdrawing the shelf in order that it may be shifted from a higher to a lower level; to 15 so construct the uprights that the collection of dust is prevented, and to provide for free ventilation.

The invention consists in the employment of uprights thicker at their rear than at 20 their forward edges thereby forming an outwardly flaring structure. The shelf is wider at its front than at its back edge. In this way when the shelf is partly withdrawn all binding of the shelf is prevented.

25 The shelves are supported by a series of lugs formed on the uprights. These lugs are preferably stamped from or otherwise formed on the uprights which are preferably of sheet metal. By the formation of 30 these lugs openings are formed in the uprights causing dust to collect therein. Therefore this invention provides means for closing the openings caused by the formation of the lugs. This means in the form of 35 a dust guard may be either a lining placed inside the hollow upright or a sheet metal strip within the lugs.

The shelf is preferably formed of sheet metal and provided with supporting ledges 40 at its ends for engaging the lugs on the uprights. Rearwardly of the ledges the shelf is provided with recesses of a width and depth slightly greater than the width and depth of the lugs whereby when the shelf 45 is partly withdrawn the recesses will aline with the lugs and the shelf may be raised from a higher to a lower level without being entirely withdrawn from between the uprights. The supporting ledges are prefer- 50 ably provided with depending lugs which engage the recesses formed in the lugs so as to prevent the shelf from being jarred out of place. In order to provide for free ventilation the shelf is preferably provided 55 with depressions or apertures, or both, stamped and punched therein.

Although in the preferred form the lugs are directly pressed from the sheet metal uprights these lugs may be formed on a separate sheet metal strip which can be riveted or otherwise secured to the uprights. The shelf may also be supported at its back edge if desired, this support being preferably in the form of a lug stamped from the attaching flanges of the sheet metal uprights. 60

Certain features of the invention may be employed in any kind of shelving whether formed of sheet metal, cast iron or of wood.

In the drawings: Figure 1 is a perspective view showing a portion of the shelving; Fig. 2 is a cross section through one of the uprights above one of the shelves showing the shelf in place; Fig. 3 is a like cross section showing the shelf partly withdrawn; Fig. 4 is a section through one of the lugs 75 on the line 4—4 Fig. 1; Fig. 5 is a section on the line 5—5; Fig. 5^a shows a modified form of this invention; Fig. 6 is a plan view; Fig. 7 is an elevation of a modified form of this invention; Fig. 8 is a section on the line 8—8 Fig. 6; Fig. 9 is a section on the line 9—9 Fig. 6; and Fig. 10 is an end view of the shelf. 80

Referring to Figs. 1 to 4 inclusive, 11 designate the sheet metal uprights which are secured to the wall or back 12 by means of screws through the flanges. A series of rows of lugs 13 are formed on the uprights. These lugs are formed by cutting through the sheet metal and pressing or stamping the lugs therefrom. The shelf 14 which is preferably formed of sheet metal is provided with ledges 15 coöperating with the lugs to support the shelves. A series of recesses 16 are formed in the ends of the shelf back of 95 the ledges 15. The ledges 15 are provided with a series of depending lips 17 which when the shelf is in place enter the recesses 18 formed in back of the lugs 13 and thus prevent the shelf from being jarred out of place. 100

It will be noted that the uprights 11 are so constructed as to be thicker at their rear than at their forward edges thereby forming a flared structure. The shelves have their ends tapering inwardly to correspond with the flare of the uprights. In this way when the shelf is partly withdrawn, as shown in Fig. 3, all binding is prevented. The width and depth of the recesses 16 is slightly 110 greater than the width and depth of the lugs 13. In this way when the shelf is partly

withdrawn, as shown in Fig. 3, it may be readily shifted from a higher to a lower level. When the shelf is pushed back in place the lips 17 will drop into place in the recesses 18 and the shelf is securely held in place. It will of course be obvious that the distance between the bottom of the lug and the top of the shelf must be less than the vertical distance between the lugs so as to give a clearance and thereby allow the shifting of the shelf.

Due to the formation of the lugs a series of openings are formed in the sheet metal uprights which will cause dust to collect therein. This objection is overcome by providing dust guards to close the openings. Figs. 1 and 4 show the preferred form which consists of a long and thin strip 19 which fits in the lugs and thereby closes the openings. These dust guards have been omitted in the remaining figures for the sake of clearness. The thickness of the strip in Fig. 4 is exaggerated for the sake of clearness. In practice this strip will be very thin. Another form of dust guard is shown in Fig. 3 consisting of a thin lining 20 riveted or otherwise secured to the sheet metal uprights. The tops of the uprights are provided with suitable closure caps not shown in the drawings.

In the construction shown in Fig. 5, and also shown in Fig. 5^a, the lugs are formed on a strip 21 secured to the uprights by means of rivets 22. In this construction the upright bodies may be formed of wood and the dust guards may be dispensed with.

In the construction shown in Figs. 6 and 7 the shelf is supported by one or more lugs at its edge and by lugs at its back edge. These lugs 23 are preferably formed integral with the attaching flanges 24 by pressing the same outwardly therefrom. The shelf 25 is provided at its end with the usual depending lip 26 engaging the recesses behind the lugs 13 and the back is supported by the lug 23 engaging the bead 28 formed at the rear edge of the shelf. Although the shelf is shown as supported at its end by a single lug 13 formed on the upright it will be obvious that the upright may be provided, as in the construction shown in Fig. 1, with an additional row of lugs. When such a construction is used however the lugs 23 must be spaced a suitable distance in order to give a clearance to allow the shelf to be lifted at its back end and disengage the rear depending lug from the recess in the lug 23.

The shelf is preferably provided with some form of ventilating means. This ventilating means is shown in Figs. 6, 8 and 9 in the form of holes 29 punched in the shelf, or depressions 30 stamped or pressed therein. Either form may be used or both forms 65 may be used in a single shelf.

In all of the above described forms the shelf and uprights are so constructed that when the shelf is partly withdrawn all binding between the shelf and uprights is prevented and it may be shifted from a higher to a lower level without entirely withdrawing it. By the provision of dust guards the collection of dust within the hollow uprights is prevented. In practice a series of uprights 11 are secured to the back or wall 70 12, two adjacent uprights supporting a series of shelves. By providing a suitable number of lugs 13 the height or spacing of the shelves may be adjusted as desired.

It is obvious that various changes in the details of construction may be made without departing from the spirit of this invention, and it is therefore to be understood that this invention is not to be limited to the specific construction shown and described.

What I claim is:

1. In library shelving, in combination, a plurality of uprights provided on their adjacent faces with spaced supports, a shelf arranged horizontally between said uprights and having stationary ledge structures arranged in spaced relation on the opposite ends of the shelf to engage the supports and serving to permit the shelf to be moved into engagement with any of the supports without wholly withdrawing the shelf from its position between the uprights and without tilting the shelf.

2. In library shelving, in combination, a plurality of uprights each including converging side portions provided on their remote faces with spaced supports, a plurality of shelves arranged horizontally between said uprights and having stationary ledge structures arranged in spaced relation on their opposite ends to engage the supports and serving to permit the shelves to be independently moved into engagement with any of the supports without wholly withdrawing the shelf from its position between the uprights and without tilting the shelf.

3. In library shelving, in combination, a plurality of uprights each including converging side portions provided on their remote faces with spaced supports, a plurality of shelves arranged horizontally between said uprights and having inclined ends provided with stationary ledge structures arranged in spaced relation on said ends, said ledge structures being adapted to engage the supports and serving to permit the shelf to be moved into engagement with any of the supports without wholly withdrawing the shelf from its position between the uprights and without tilting the shelf.

4. In shelving, the combination with a series of uprights, of movable and substantially rectangular shelves arranged between said uprights, spaced edges having spaced

- supports for supporting said shelves at different adjustable levels, the engaging portions of said shelves, uprights and supporting means being constructed so that a transverse movement of a shelf with respect to said uprights will cause said shelf to clear said uprights and supporting means.
5. In shelving, the combination with a series of uprights provided with shelf supporting lugs, of a shiftable shelf arranged between said uprights, said shelf being provided with ledges arranged to coöperate with said lugs, and with recesses arranged to aline with said lugs, said shelf and uprights being constructed to permit said shelf to be moved transversely with respect to said uprights, for the purpose set forth.
6. In shelving, the combination with a series of uprights provided with shelf supporting lugs, of a shiftable shelf supported at its edges on said lugs, said shelf having recesses formed in its edges and arranged to aline with said lugs, said shelf and uprights being constructed to permit said shelf to be moved transversely with respect to said uprights, for the purpose set forth.
7. In shelving, the combination with a series of uprights each provided with horizontally arranged lugs, a pair of said lugs 30 on opposite faces of said uprights projecting inwardly beyond another pair, of a shiftable shelf having stationary supporting ledges arranged in spaced relation at its ends to coöperate with said lugs, the forward ledges projecting outwardly beyond the rear ledges.
8. In shelving, the combination with a series of flaring uprights having shelf supporting lugs thereon, of a shiftable shelf 40 having its ends tapering and arranged between said uprights, said shelf being provided with ledges coöperating with said lugs and with recesses arranged to aline with said lugs, said shelf and uprights being constructed to permit said shelf to be moved transversely with respect to said uprights, for the purpose set forth.
9. In shelving, the combination with a series of outwardly flaring uprights 50 provided with a series of shelf supporting lugs, of a shiftable shelf provided with ledges coöperating with said lugs, said shelf having recesses located back of the ledges and arranged to aline with said lugs.
55. 10. In shelving, the combination with a series of uprights having a series of lugs stamped or formed integral therewith, of a shiftable shelf provided with depending lips for engaging the recesses formed within the lugs, said shelf having recesses located back of the lips and arranged to aline with said lugs.
11. In shelving, the combination with a series of uprights having supporting lugs thereon for the ends and the back of the shelf, of a shiftable shelf provided with end supporting ledges, and with recesses back of the ledges arranged to aline with some of said lugs, for the purpose set forth.
12. In shelving, the combination with a series of one piece sheet metal uprights having shelf end supporting lugs and back supporting lugs stamped therefrom, of a shelf constructed to be supported by said lugs.
13. In shelving, a sheet metal upright having an attaching flange, an end supporting lug pressed from the body, and a back supporting lug pressed from the flange.
14. In shelving, an upright including a sheet metal body portion having lugs pressed therefrom and a strip fitting within the lugs and closing the openings caused by the formation of the lugs.
15. In shelving, a hollow sheet metal upright having lugs pressed therefrom, and a sheet metal lining fitting within the upright and constructed to close the openings caused by the formation of the lugs.
16. In shelving, a sheet metal upright having a series of vertical rows of lugs pressed therefrom, and a sheet metal strip for each row fitting within the lugs.
17. In shelving, the combination of uprights thicker at their inner than at their outer edges, having a plurality of series of narrow supporting lugs thereon, and a shelf having lips to engage with the lugs and recesses back of the lips, whereby the position of the shelf within the uprights may be changed without completely withdrawing it therefrom.
18. In shelving, the combination of uprights, each having a series of narrow supporting lugs thereon, and a shelf having lips to engage with the lugs and recesses back of the lips as great in width as the width of the lugs, whereby the position of the shelf on the uprights can be changed without completely withdrawing it therefrom.

In testimony whereof I affix my signature in presence of two witnesses.

JAMES W. HINE.
